ica, a corporation of Delaware

Application April 23, 1948, Serial No. 22,848

8 Claims. (Cl. 250—153)

1

This invention relates to cathode ray tubes, and in particular to storage tubes of the cathode ray type in which a charge pattern is established on the insulating surface of the target electrode of the storage tube by signals applied to the signal plate of the target, while an electron beam scans the insulating target surface. The output signal of the tube is that provided by a modulated secondary emission from the insulating target surface. A tube of this type is disclosed in the application of R. L. Snyder, Jr., filed July 24, 1945, Serial No. 606,812.

Tubes of this type utilize a magnetic field, established parallel to the tube axis and perpendicular to the target surface, for focusing the scanning electron beam on the target and for directing the secondary emission back along the beam path toward the collector electrode. Tubes using the same field for focusing both the primary electron beam and the secondary emission are subjected to a non-uniform collection of secondary emission over the target surface. Also due to the design of such tubes, changes made to improve secondary collection from the target tend to cause defocusing of the scanning electron beam and loss of resolution of signal.

Furthermore storage tubes of this type utilize appropriate electromagnetic coils for establishing the required scanning fields. Elimination of the scanning coils would greatly reduce the weight as well as the power requirements in large tubes of this type. Also, a long magnetic scanning field is impractical for tubes having targets two inches and more in diameter. Consequently, in large storage tubes, of the type described, magnetic scanning has proved impractical.

Accordingly, it is an object of this invention to provide an improved storage tube of the cathode ray type.

It is also an object of this invention to provide a storage tube having uniform collection of signal from the target surface.

It is a further object of this invention to provide a storage tube in which the collection of signal current from the target is not dependent upon the electron beam focusing fields.

It is also an object of this invention to provide a storage tube in which the primary electron beam is little effected by the collecting fields for the signal electrons.

The novel features which we believe to be characteristic of our invention are set forth with particularity in the appended claims, but the invention itself will best be understood by reference to the following description taken in connection

with the accompanying drawing, in which the single figure is a cross-sectional view of a storage tube according to the invention.

The drawing discloses a storage delay tube of the cathode ray type comprising an envelope 10 of glass or any other suitable material. Within the envelope is positioned an electron gun for the purpose of forming and focusing an electron beam upon a target electrode 30. The gun structure consists of a thermionic cathode 12 surrounded by an apertured control grid 14. Mounted in alignment with the opening through the control grid is an anode electrode 16 for accelerating the electron emission from the cathode 12 and for focusing the electrons of the beam onto the surface of a target 30 mounted at the other end of the envelope 10. Two pairs of deflecting plates, respectively 18 and 20, are positioned along the beam path between the anode electrode 16 and the target 30. As is well known in the art, these pairs of deflecting plates each produce electrostatic fields at right angles to each other and to the path of the electron beam. It is understood that these plates respectively will have varying voltages applied, say by a saw-tooth generator, to produce line and frame scansion, or appropriate voltages may also be applied to deflection plates 18 and 20 for producing spiral scansion of the target, or line scansion only, as may be desired. The means for producing different types of scansion of the target surface 30 are well known in the art and need not be further described.

The operation of the tube depends upon a signal being generated by the emission of secondary electrons from the target 30, when bombarded by the electron beam. A collector electrode 28, in one type of tube as shown in the figure, comprises an open-ended cylinder 28 mounted in the envelope 10 coaxial with the electron beam path and so that the beam will pass through the cylinder 28 after deflection by plates 18 and 20. Electrodes 22, 24 and 26 are shield electrodes formed from apertured metal discs and spaced along the path of the electron beam. Electrode 24 is arranged so that the beam passes through the central aperture thereof and it forms an electrostatic shield between the plates 18 and the plates 20. Similarly, electrode 26 is an apertured disc coaxially spaced along the electron path and positioned between the deflection plates 20 and the collector electrode 28. Shield electrode 26 not only shields collector 28 from the signal of deflection plates 20, but also maintains axial symmetry of the electron lens fields in the target

section to eliminate one type of astigmatism in the beam. Shield electrodes 24 and 26 may be maintained at the potential of the focusing anode electrode 16.

The target electrode 30 comprises essentially a metal support plate 32 mounted transverse to the path of the electron beam and which functions as the signal plate of the target electrode. On the surface of the signal plate 32, facing the electron gun, is fixed a dielectric layer 34, such as mica. Target 30 may also be formed, using an aluminum signal plate, having a dielectric surface of aluminum oxide, facing the electron beam, formed, for example, by anodizing the aluminum. However, the construction of the target 30 need not be confined to either of these described forms, but may be of any other appropriate insulating material such as titanium dioxide, or silicon dioxide, for example, deposited in any manner as evaporation or thermal decomposition upon a conductive signal plate. In the figure, closely spaced from the exposed surface of the mica layer 34, is a fine mesh screen 36 or barrier grid which may be mounted by a supporting ring 38 at a few mils from the surface of the dielectric layer 34.

As the dielectric surface 34 is scanned by the electron beam, secondaries are emitted and drawn away toward collector electrode 28 which is maintained during tube operation, at a high positive potential relative to the potential of surface 34. Since the secondary electrons from the dielectric surface 34 are emitted in all directions at relatively low velocities, electrodes 40 and 42, maintained during tube operation at different potentials, are used to form a focusing electrostatic field for directing the secondary emission into the collector cylinder 28. A shield electrode 44 comprising an apertured plate is mounted, as is shown, and shields collector electrode 28 from voltage fluctuations produced on the target 30 by incoming signals.

The principle of electrostatic storage on an insulating surface has long been known and used in television pickup tubes, such as the iconoscope. If an insulating surface is bombarded by an electron beam, the secondary emission ratio will vary with the energy of the bombarding electrons. If the energy is such that the secondary emission ratio is greater than unity, then the potential of the target surface will change with respect to the electrode which collects the secondaries, until the net number of secondaries leaving the target surface is exactly equal to the number of primaries arriving there. The surface potential, at which this action takes place, is known as the equilibrium potential. The remaining secondary electrons collect in the form of a space charge and rain back on the insulating surface, charging the unbombarded parts of the surface to a negative potential. Thus, a charge pattern is built up on the surface in the absence of any applied signal. The returning electrons, of course, partially neutralize any charges already on the surface and, thus, would make any comparison of signals from scan to scan impossible. Several ways have been attempted in the past to eliminate this electron redistribution effect. Screen 36, mounted close to the insulating surface 34, eliminates this redistribution effect, as described below.

In operation, the electron beam strikes the dielectric surface 34 with sufficient velocity to produce a secondary emission ratio greater than unity. To obtain this condition, the screen 36 and signal plate 32 in the specific tube described

are maintained at a potential about eleven hundred volts positive relative to the cathode 12 of the electron gun, which may be considered to be at ground potential. Wherever the beam strikes the dielectric 34, the potential of the elemental area of the surface under bombardment becomes the same or nearly the same as that of the screen 36; that is, equilibrium conditions exist only at this potential.

Since target surface 34 is an insulator, the only source of current to it is the primary beam, and the only drain of current from it is the secondary electron emission. At equilibrium, these two must be equal, and any deposition or removal of charge on the surface 34 will appear as a modulation of the secondary electron emission. However, since the energy of the primary electrons, when they strike the dielectric, is such that the secondary emission ratio is greater than unity (actually about two), those secondary electrons in excess of the number arriving in the primary beam must return to the target surface to maintain the target surface 34 at equilibrium potential.

The barrier grid or screen 36 functions as a virtual collector, so that the equilibrium potential of the target surface 34 is established with respect to screen 36 and not to the actual collector electrode 28. At this potential, a number of secondaries, just equal to the number of arriving primaries, are sufficiently energetic to penetrate screen 36. These cannot return to the target, as appropriate fields outside the screen urge them away and toward collector 28 as the secondary beam. Meanwhile, the excess electrons are not sufficiently energetic to reach screen 36 from surface 34, and are restricted in their motion by the close proximity of the screen to the dielectric surface 34, so that their redistribution to portions of the target not directly under the beam is considerably reduced.

In normal operation, the screen 36 over the target surface 34 is maintained at a direct current potential and the conductor plate 32 is connected to a source of the signal to be recorded. The insulating surface 34 is therefore capacitively coupled to the signal plate 32 and also has capacity to the screen 36. When a signal voltage is impressed on signal plate 32, it also appears, somewhat diminished in amplitude, on the recording surface 34 of the target.

If a signal is applied to plate 32 so that it is driven negative relative to the equilibrium or screen potential then any elemental area of surface 34 under bombardment, at the time by the electron beam, will also be negative relative to the screen. Under these conditions, a positive field between screen 36 and target 30 will be presented to the surface 34 and, therefore, all of the secondary electrons, released by the impact of the beam electron, are drawn away. Since the number of secondary electrons is greater than the number of primary electrons, there is a net loss of negative charge and the elemental surface area becomes more positive. If, however, the element of surface 34 is positive with respect to the screen at the time of bombardment due to an incoming signal driving plate 32 in a positive direction, a negative field exists between the surface 34 and the screen 36 so that fewer secondary electrons are sufficiently energetic to penetrate the screen and more are returned to the element of surface 34 from whence they came. Since there are less secondary electrons leaving than primary electrons arriving at the element, there is a net gain.

of negative charge and the potential of the surface becomes more negative.

When target plate 32 is at the potential of screen 36 or a little positive thereto, there are just as many secondary electrons escaping through the screen as there are primary electrons arriving. This condition of equilibrium exists at a potential a few volts positive with respect to the screen 36 because the initial velocity of most of the secondary electrons is sufficient to lift them over a potential barrier of several volts. The exact potential is not very definite, because it is affected by space charge conditions, the geometry of screen 36 and nearby electrodes, and the energy distribution of the secondary electrons. Fortunately, the value of the equilibrium potential has no great influence on the operation of the tube as long as it remains practically constant.

As the beam is deflected across the surface 34, while a signal is impressed on the signal plate 32, it will cause each element of surface area it strikes to come to screen potential, regardless of the potential the surface would otherwise have due to the influence of the signal plate. This action, then establishes a charge between the signal plate 32 and the surface element which will cause the element to have a potential different from that of the screen 36 when the beam moves off of the surface element and the signal plate 32 returns to equilibrium potential. If the beam scans a long path over the target surface 34, while a fluctuating voltage is impressed on the signal plate 32, a band of charges, as wide as the beam, will remain on the path when the beam is cut off. If the signal plate 32 returns to equilibrium potential, the potential along the path will vary in proportion to the signal voltage impressed during the beam transit.

When the electron beam scans the target 30, some of the secondary electrons directed toward collector electrode 28, are from the solid parts of the screen, which intercept the beam current. The rest of the secondary electrons come from the surface of the dielectric. Those electrons released from the screen are essentially constant in number, because the beam current is fixed and the secondary emission ratio over the screen is quite uniform. Also, the screen 36 is fine enough to average out geometrical effects. The secondary emission from the dielectric surface, however, fluctuates according to the charging demand. If no change of charge is required by an element, the secondary electrons released therefrom are equal in number to the impinging beam electrons. If a negative charge is to be supplied to the dielectric surface 34 to bring the elemental target area to equilibrium potential, secondary emission is suppressed until the demand has been satisfied. If a positive charge is needed to bring the target area to equilibrium the secondary emission is a maximum until full charge is achieved.

In the known coherent pulse radar system, the signal pulses are transmitted at the beginning of each line scansion at the peak of the saw-tooth wave controlling this scansion. Echo signals from both moving and stationary objects are received and mixed with a continuous wave signal of a local oscillator to produce a heterodyned signal which is impressed on the target 30 in certain phases of the line scansion, of the storage tube, depending upon the distance of the objects from the transmitter receiver. The successive echo signals from fixed objects will be beat signals of fixed amplitudes, while the echo sig-

nals from moving objects will be beat signals whose amplitudes vary with the Doppler frequency. A charge put down on an elemental area of the dielectric surface 34 by the electron beam, when the potential of the surface was changed from the equilibrium value by a signal echo from a stationary object, will maintain the elemental area at equilibrium potential during succeeding line scans of the target. However, echo signals from moving objects arriving with a changing amplitude will cause the elemental target areas struck by the beam to change in potential. Thus, the secondary electron emission will be constant from the target areas charged during the reception of signals from fixed objects, while the secondary emission will vary from target areas charged during reception of signals from moving objects. This varying secondary emission will be the alternating current component of the secondary emission current in the output circuit of the tube. Thus, only signals from moving objects will be detected by the storage tube described.

The dielectric layer 34 of the target 30 must have a sufficiently high product of resistivity and dielectric constant so that an appreciable amount of charge cannot leak through the dielectric layer 34 between scans. Also there must be so little surface leakage across the dielectric, and the successive lines of the scan must be sufficiently spaced relative to the spot size of the beam, that the beam cannot remove the charge that was deposited when it previously scanned a neighboring line.

The spacing of screen 36 from the mica surface 34 is not too critical. However, if the spacing is too great there will be a redistribution of the secondary emission which does not penetrate the screen but falls back onto the target surface and which will tend to discharge positive areas of the target other than that which the beam is striking. This effect will tend to produce a shading of the signals and also reduce the resolution of the signal collected. Also if the spacing is too small, whenever negative signals are applied to the signal plate 32, the very negative portion of the target surrounding the beam spot may create a negative field which will erect a potential barrier producing a negative grid effect suppressing the secondary emission and forcing the secondaries back to the screen 36. As a result these electrons will be collected by the screen 36 and their absence from the secondary beam on each scan will cause a positive signal to appear in the collector circuit.

The screen electrode 36 in one form of the tube shown in the drawing, comprises a mesh screen having 230 openings per inch. A suitable material for screen 36 has been found to be stainless steel, which provides sufficient strength to support the screen at its desired spacing from the dielectric surface 34. As the electron beam scans across the wires of the screen 36, a noticeable modulation of the secondary electron signal collected by the electrode 28 is produced due to the difference in secondary electron emission of the screen 36 and the dielectric surface 34. Since it is desirable that the secondary emission ratio of the screen 36 be approximately unity, during tube operation, the stainless steel screen 36 is coated by a layer of sputtered gold or other suitable materials having a secondary emission ratio close to unity such as carbon, for example.

The transmission of screen 36 is approximately

50 percent of the impinging electron beam. However, if a coarser mesh screen were used, there would be a greater redistribution of the secondary emission electrons suppressed by the screen. The screen 36 functions as an electrostatic shield to prevent the redistribution of secondary electrons to other positive portions of the dielectric surface.

As the dielectric surface 34 of the target is bombarded with electrons of the primary beam, the secondary electrons from the dielectric surface 34 and also from the wire mesh screen 36 will be emitted in all directions. These secondary electrons which leave the target area must be properly focused and directed toward the collector electrode 28 in an efficient manner. To accomplish this, electrodes 40 and 42 are provided. Electrode 40 comprises a conductive coating on the inner surface of the envelope wall 10 and conforms to the cylindrical shape of the tube envelope. Coating 40 extends so that one end overlaps and encloses the barrier grid 36 and the dielectric target surface 34. Electrodes 40 and 42 may also be cylindrical metal electrodes mounted within the tube envelope. Wall electrode 40 is preferably maintained at the potential of the barrier grid 36. Electrode 42 is spaced from electrode 40 and is maintained in the specific tube described at a potential of between one hundred and two hundred volts positive to the potential of electrode 40. The arrangement of electrodes 40 and 42 provides a converging focusing electrostatic field therebetween, when appropriate voltages are applied during tube operation. This converging field, between electrodes 40 and 42, will tend to direct the secondary emission from the target 30 toward the axis of the tube envelope 10.

In this manner, the secondary emission originating from the insulating surface 34 and the screen 36 will be directed toward the axis of the tube from all positions of the target surface struck by the electron beam. This arrangement provides a uniform collection of secondaries from all of the target surface so that there is little or no resultant shading of the signal.

The collector electrode 28 is operated at the highest potential in the tube so that as the secondaries are directed back toward the axis of the tube they will pass into a region close to electrode 28 at which they come into the field of the lens formed by collector 28 and the aperture in electrode 44. Those secondary electrons, emitted principally from the central portion of the target 30, will tend to pass down the axis of the tube toward the cathode of the electron gun. To prevent these secondary electrons from passing completely through the collecting cylinder 28 and hence being lost and contributing by their absence a positive disturbance signal, shield electrode 26 is positioned so that when it is maintained at a potential somewhat negative to the target surface 34, electrode 26 will act as an electrostatic mirror. Thus electrode 26 will provide a negative barrier field to the secondary electrons and prevent their passage through the collector cylinder 28 and secondaries attempting to pass through the collector cylinder 28 will be reflected back and swept up by the positive field of electrode 28.

Electrode 44 is provided with an aperture large enough for the passage therethrough of the secondary signal electrons. However, it is arranged as is shown in the figure to electrostatically shield the collector electrode 28 from the fluctu-

ating potentials applied on the signal plate 32 of the target electrode by incoming signals. Furthermore, the mirror or barrier electrode 26 serves to shield the collector electrode 28 from the fluctuating scanning potentials applied to the pair of deflection plates 20. This shielding of the collector electrode 28 thus prevents the picking up of spurious signals produced by capacity effects with other electrodes in the tube having fluctuating potentials applied during tube operation.

The various voltage and potential values indicated in the figure and described above are given only as illustrative of those used in a successfully operated tube of this type. The invention is not confined to these values and other potentials may also be used successfully.

We have described the operation of our storage tube in connection with a moving target indicating radar system, but this is by way of example only. The improved storage tube may be used in various other ways where storage of information is desired. Signals may be impressed on the signal plate while the beam scans a predetermined pattern over the target. The signal and beam may then be shut off, leaving the information stored in the target. At any desired later time the beam may be turned on and, with no new signals impressed on the signal plate, scanned over the pattern so that the signal impressed during the first operation will be reproduced. The signals need not be recorded in one scansion and utilized in the next scansion. Signals can be stored at one time and reproduced at any later time merely by shutting off and turning on the beam at the desired times. In some tubes of the type described, signals have been stored on the target surface up to one hundred hours with little loss of definition. As will be evident from the described method of operation, recorded signals may be combined with new signals, enabling one to use the tube for carrying out complex operations by suitable combination of signals.

While certain specific embodiments have been illustrated and described, it will be understood that various changes and modifications may be made therein without departing from the spirit and scope of the invention.

What we claim as new is:

50. 1. A cathode ray tube comprising an evacuated envelope, means within said envelope for forming a beam of electrons along a path, a target electrode mounted within said envelope in the path of said electron beam, said target electrode having a surface providing secondary electron emission when struck by said electron beam, a collector electrode mounted within said envelope between said beam forming means and said target, and a plurality of electrodes within said envelope between said collector electrode and said target for focusing the secondary emission adjacent said collector electrode.
55. 2. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, and electrostatic means for focusing said secondary electron emission near said collecting electrode.
60. 3. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, and electrostatic means for focusing said secondary electron emission near said collecting electrode.
65. 4. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, and electrostatic means for focusing said secondary electron emission near said collecting electrode.
70. 5. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, and electrostatic means for focusing said secondary electron emission near said collecting electrode.
75. 6. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, and electrostatic means for focusing said secondary electron emission near said collecting electrode.

3. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, a plurality of electrodes enclosing the path of said electron beam for focusing said secondary electron emission near said collecting electrode.

4. A signal generating device comprising an evacuated envelope, electron gun means within said envelope for forming a beam of electrons along a path, a target electrode within said envelope intercepting said electron beam path, said target electrode having a surface providing secondary electron emission when struck by said electron beam, an electrode within said envelope for collecting said secondary electron emission, said collecting electrode having an aperture therethrough for passage of said electron beam, means for directing said secondary electron emission toward said collecting electrode, said directing means including a shield electrode between said target electrode and said collecting electrode and a plurality of electrodes between said shield electrode and said target for focusing said secondary electron emission into the aperture of said collecting electrode.

5. A cathode ray tube comprising an evacuated envelope, electron gun means within said envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, means for directing said secondary electron emission toward said collecting electrode, said directing means including an apertured shield electrode mounted within said envelope coaxially with said collecting electrode and between said collecting electrode and said target and a plurality of electrodes between said shield electrode and said target for focusing said secondary electron emission through said shield electrode into the aperture of said collecting electrode.

6. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam,

5 electrostatic deflection means for causing said electron beam to scan said target surface, means for electrostatically shielding said collecting electrode from said deflection means and said target, and a plurality of electrodes between said collecting electrode and said target for focusing said secondary electron emission into the aperture of said collecting electrode.

7. A cathode ray tube comprising an evacuated envelope, electron gun means within said envelope for forming a beam of electrons along a path, a target electrode mounted within said envelope to intercept said beam of electrons, said target electrode having an insulating surface providing secondary electron emission when struck by said electron beam, an electrode within said envelope for collecting said secondary electron emission, said collecting electrode having an aperture therethrough for passage of said electron beam, plate electrodes mounted within said envelope between said gun and said collecting electrode for causing the electron beam to scan said insulating target surface, a first shield electrode between said deflecting plate electrodes and said collecting electrode a second shield electrode between said collecting electrode and said target, and electrostatic means for focusing said secondary electron emission into the aperture of said collecting electrode.

8. A cathode ray tube comprising an evacuated envelope, electron gun means within said envelope for forming a beam of electrons along a path, a target electrode mounted within said envelope to intercept said beam of electrons, said target electrode having a surface providing secondary electron emission when struck by said electron beam, an electrode within said envelope for collecting said secondary electron emission, said collecting electrode having an aperture therethrough for passage of said electron beam, a plurality of plate electrodes mounted within said envelope along the path of said electron beam between said electron gun and said target, for causing said electron beam to scan the surface of said target, a first shield electrode mounted between said plate electrodes and said collecting electrode, a second shield electrode mounted between said collecting electrode and said target, each of said shield electrodes having an aperture therethrough for passage of said electron beam, and a plurality of electrodes between said second shield electrode and said target for focusing said secondary electron emission into the aperture of said collecting electrode.
